UNITED STATES PATENT OFFICE.

JULIUS G. PEGEL, OF THOMPSONVILLE, CONNECTICUT, ASSIGNOR TO THE HARTFORD CARPET CORPORATION, OF THOMPSONVILLE, CONNECTICUT, A CORPORATION OF CONNECTICUT.

DESIGN FOR CARPET OR RUG.

42,059.

Specification for Design.

Patented Dec. 26, 1911.

Application filed October 17, 1911. Serial No. 655,233. Term of patent $3\frac{1}{2}$ years.

To all whom it may concern:

Be it known that I, JULIUS G. PEGEL, a citizen of the United States, and residing in Thompsonville, in the county of Hartford and State of Connecticut, have invented a new, original, and ornamental Design for a Carpet or Rug, of which the following is a specification, reference being had to the accompanying drawing, forming part thereof.

The figure is a face view of a carpet or rug showing my design.

I claim:

The ornamental design for a carpet or rug as shown.

JULIUS G. PEGEL.

Witnesses:

JAMES L. FOLSOM,
GEO. S. SQUIRE.
